UNITED STATES PATENT OFFICE.

NICOLAI MINORSKY, OF BELMAR, NEW JERSEY.

DIRECTIONAL STABILIZER.

Application filed September 21, 1922. Serial No. 589,627.

This invention relates to the control of stabilization of ships, airships, airplanes and the like, in response to the combined effect of the angular deviation of the body to be stabilized from its predetermined direction, and also of one or more time derivatives of this deviation.

The advantages of controlling the stabilization in response to such a combination of dynamical elements have been set forth at length in my Patent 1,436,280, of November 21, 1922, entitled "Automatic steering device". In that application I describe specifically a helm controlling device for a ship, so arranged that the movements of the rudder are affected in response to the yawing of the ship off her course, and to a plurality of higher time derivatives of the yawing, especially the velocity and the acceleration of the yawing. It is possible to demonstrate mathematically that it is essential to control the rudder or other stabilizing device in response to such a function, in order that the directional stability along the course be performed in a substantially perfect "dead beat" manner; and if on the contrary this control be made responsive solely to the extent of deviation from the predetermined direction, oscillations of the controlled body about the desired line of stabilization cannot be prevented. The principles involved for proper "dead beat" stabilization are of course applicable to other cases where it is desired to maintain the relative position of a body fixed with respect to a reference line or to another body. Such a case, for example, arises in connection with airplanes where stabilization may be desirable about more than one axis.

It is one of the objects of my invention to provide a comparatively inexpensive and simple device for effecting substantially the same results as in my prior application. Furthermore the present application describes a device having comparatively small weight, so that it is especially applicable for the stabilization of airplanes.

Another object of my invention is to provide a controlling device for stabilizing which is devoid of either gyroscopes or follow up devices, and instead makes use of stationary electrical apparatus with substantially no contacts to be made and broken. The avoidance of contact making devices is

of especial importance where the control is mounted on bodies subject to violent vibrations, such as airplanes, since such contacts as is apparent may be seriously and objectionably affected by these vibrations.

Another advantage secured by my invention resides in the degree of facility with which the control may be adapted to any particular body to be steered or stabilized, and to vary the performance of the control to suit weather conditions or the requirements of navigation either in the air or on the water at any time. To produce these variations or adjustments with my controlling device is an extremely simple matter, as it may be effected by adjustment or tuning of the electrical constants of controlling circuits, as for example by a variation in inductance or resistance, or both.

To provide this simplicity of control, I make use of a device that is moved in and influenced by the earth's magnetic field so as to generate an E. M. F., such as a constantly revolving armature of the direct current type. It is thus another object of my invention to utilize as a control element a device for generating an E. M. F. by rotation in the terrestrial magnetic field.

It is still another object of my invention to provide an extremely simple manually operated steering device by which it is possible to set the course of the body so that the automatic control will bring the body back to that set course in response to functions of its deviation.

My invention possesses many other advantages, and has other objects which may be made more easily apparent from a consideration of various embodiments of the invention. For this purpose I have shown several forms of my invention in the drawings accompanying and forming part of the present specification. I shall now proceed to describe in detail these forms, which illustrate the general principles of my invention, but it is to be understood that this detailed description is not to be taken in a limiting sense, since I intend the scope of my invention to be defined by the appended claims.

Referring to the drawings:

Figure 1 is a wiring diagram of one form of control embodying my invention;

Fig. 2 is a diagrammatic longitudinal sec-

tional view of that element of my device which is adapted to be affected by the earth's magnetic field;

5 Fig. 3 is a sectional view taken along line 3-3 of Fig. 2;

Fig. 4 is a wiring diagram of a modified form of my invention;

Fig. 5 is a diagrammatic view of a still further modification;

10 Fig. 6 is a wiring diagram showing the use of a modified form of thermionic relays or amplifiers used in the circuits of Fig. 1; and

15 Fig. 7 is a vector diagram illustrating the behavior of the instrument shown in Figs. 2 and 3 under certain conditions.

In Fig. 1, I illustrate an instrument 11 having a rotating element 12, which is arranged to be influenced by the terrestrial magnetism. The direction of the horizontal component of 20 this field is represented by the large dotted arrow 13 the point of which is labelled "North", and is shown in this instance to be substantially perpendicular to the axis of rotation of the element 12. This element is constructed like 25 an ordinary bipolar direct current armature, as indicated more clearly in Fig. 2, and is provided with a commutator 14 upon which bear the brushes 15, 16. Any appropriate source 30 of motion such as a motor 17 may be arranged to rotate the armature 12, as by direct connection to the shaft 18 of the armature. The electromotive force which is induced across the brushes 15, 16, due to the motion of armature 11 in the terrestrial field, depends, among 35 other things, upon the relative position of the brush axis and of the axis of the field through which the armature sweeps. In the present instance it is assumed that when the brush axis is parallel with the direction of the earth's 40 field as illustrated in Fig. 1, the potential difference across the brushes is a minimum, or zero. As is well understood, deviation of the brush axis from this position causes the potential difference to be increased substantially 45 as a sine function of the angle of deviation. Furthermore it may be assumed that a deviation in a clockwise direction, as shown by the arrow 19, results in making the upper brush 15 positive with respect to the lower brush 16. 50 Deviation in the opposite direction causes this polarity to be reversed.

By fixing the brush axis so that it has a definite direction with respect to that of a chosen axis of the body to be stabilized, deviations of 55 this latter axis from a definite direction causes corresponding variations of the induced electromotive force for influencing the stabilizing element, which may be a rudder 170 arranged to be effective by its movement to 60 bring the body back to its predetermined position. In the present instance the electric motor 20 of the direct current type is arranged to move the stabilizing element, and this electric motor in turn is fed from a 65 generator 21. This generator is controlled

in response to functions of the deviation of the brushes from the minimum or zero E. M. F. position, so as to impress upon the armature of motor 20, electromotive forces which vary correspondingly to the variations in the 70 controlling functions. The generator 21 may be driven by any appropriate source; if the installation is on an airplane, the generator may be driven by the shaft 23 carrying the screw 24 which is adapted to be rotated by the relative 75 movement of the airplane with respect to the atmosphere. The shaft 25 of the motor 20 is connected in any appropriate way to the rudder moving mechanism.

The generator 21 not only serves to transmit 80 properly the functions of the variations in the E. M. F. across the brushes 15 and 16, to the motor 20, but also serves to magnify or amplify these effects. The functions of the E. M. F. which are most useful for stabilizing the 85 body, are those due to the deviation of the brushes from zero position and derivatives of this E. M. F. with respect to time. Since the deviation of the brushes from the zero potential 90 position is equal to the deviation of an axis of the body from its required position, it is evident that the control of the stabilizing element is effected, by this means, in response to the extent of deviation of the body, in conjunction with the velocity of deviation, and if 95 necessary, with still higher time derivatives of the deviation, such as the acceleration and the velocity of acceleration.

In order to magnify or amplify the effects 100 of the deviation and its dynamical elements before they are caused to affect the generator 21, appropriate relays may be provided. These relays may be of the electromagnetic type, but in order to cause as prompt response 105 of the entire control to the conditions of the deviation as possible, I prefer to use thermionic relays, such as 26, 27, and 28. These have the further advantage that no circuits need be made or broken by them, and they act 110 in a perfectly continuous manner. Before 110 discussing in greater detail the circuits of Fig. 1 whereby these relays and the generator 21 properly affect the motor 20, it is advisable to describe in greater detail one form of the instrumentality 11 which forms the seat 115 of the controlling forces for the entire device. This instrument is shown in detail in Figs. 2 and 3.

In the present instance the instrument 11 is 120 shown as arranged to be affected by the horizontal component only of the earth's magnetic field, and in this way it may be made to stabilize a body about a definitely directed horizontal axis or course. In other words, such an instrument is of use for steering a 125 course with respect to the earth's surface. By arranging the instrument so that the armature 12 has its axis rigidly fixed with respect to the body to be stabilized, it is possible to derive controlling functions and obtain con- 130

trolling actions responsive to deviations in the position of the body not only in azimuth but also in other planes of reference. The axis of armature 12 may for example be so supported on the body that when that body is properly positioned, this axis is parallel to the axis of terrestrial magnetism which is generally known for any given locality. Deviations from this position of the body give rise to the generation of electromotive forces within the armature which may be utilized to stabilize the body against rolling and pitching, in addition to control for azimuthal or anti-yawing stabilization. Controlling effects may thus be derived for all three degrees of freedom of a body, which effects can be made responsive not only to the actual deviation in each degree of freedom but also higher time derivatives of the deviations. This response to deviation in any of the degrees of freedom is of especial importance in connection with the stabilization of airplanes and the like, the position of which is affected by any external disturbance such as winds, usually in any or all of the three degrees of angular freedom about the center of gravity of the body.

The shaft 18 of armature 12 in the embodiment of Figs. 2 and 3 is shown so chosen that it occupies a substantially constant vertical direction, irrespective of the movement of the body itself, and in this way the horizontal component only of the terrestrial magnetism is caused to affect the instrument 11. In this way variations of the body from a desired horizontal course on the earth's surface cause variations in the relative position of the brush axis and the magnetic meridian, as explained hereinbefore. The armature 12 is constructed substantially like an ordinary direct current armature, except that the number of turns of the winding in series between brushes 15, 16 is very large, so that a substantial E. M. F. may be induced across them in spite of the weakness of the terrestrial magnetism in which the armature rotates. For this reason also the armature 12 should be driven at a fairly rapid rate. The cross section of the wire may be very small indeed, since the armature has to carry minute currents only. Preferably, also, a nonmagnetic core is used for the armature, in order to prevent any distortion of the terrestrial field. The entire mechanism is enclosed in a frame 29 suspended in a Cardan suspension so as to keep the axis of armature 12 vertical. This suspension comprises the usual external gimbals 30, in which is suspended on ball bearings 31, the inner gimbals 32. This latter in turn supports on ball bearings 33 the frame 29. The axis of bearings 33 is substantially perpendicular to that of bearings 31. By providing a slight amount of pendulousness to the suspended frame 29 and its contents, the axis of armature 12 has a tendency to remain truly vertical, and is not

disturbed materially by the angular motions of pitching and rolling of the ship or other body that is being stabilized, since such motions are but little assisted by the natural period of oscillation of the device. Other temporary ballistic disturbances which cancel out over a more extended period are likewise ineffective. Located conveniently near the bottom of the frame 29 is the driving motor 17. The shaft 18 is properly supported at an intermediate point by the ball races 34, which act against a shoulder on the shaft and thus serve also as step bearings. These races are supported on the bracket 37 fixed to the interior of frame 29. At the upper end the shaft 75 is guided by the ball bearing 35, held in the cover 36 of the frame 29. The brushes 15, 16 are supported on the interior of a collar 38 rotatably mounted in bracket 39 fastened to the interior of frame 29. The collar 38 is carried 80 by a non-magnetic rectangular frame 40 encompassing the armature 12. This frame carries in turn the rectangular coils 41 and 42, the turns of which are preferably uniformly distributed along the width of the frame 40, and so arranged that their axis is perpendicular to that of the brushes 15, 16. The entire frame 40, with collar 38 and brushes 15, 16 is rotatable and is supported and guided at the bottom on the stationary collar 43, upon which 95 also rest the bearings 34. In order to rotate this frame, it is adapted to be driven by spur gears 44, 45, which are carried by the frame. The connections to brushes 15, 16 are effected by the aid of terminal posts 46 supported on the cover 36, which posts connect to the slip rings 47. These rings are supported on the projection 48 of the cover 36, and are in turn connected by auxiliary brushes to the main brushes 15, 16. The connections to coils 41 100 and 42 are effected by the aid of three slip rings 49, 50, and 51, held on the exterior of a collar 52 attached in any suitable manner to the frame 40. The particular utility of coils 41 and 42 will be described hereinafter, in 105 connection with the detailed description of the circuits of Fig. 1.

The motor 17, in addition to its function of rotating the armature 12 at a rapid rate, serves to rotate the whole frame 40 and its associated coils 41 and 42 and brushes 15 and 16, when it is desired to set these brushes to a new position with respect to the body to be stabilized. For this purpose there may be provided a worm 53 on the armature shaft 18, 115 which worm is adapted to engage a worm wheel 54 fastened on shaft 55 journaled appropriately in relatively stationary parts of the frame 29, one of which is shown as the bracket 56 and the other as the side of the 120 frame 29. Splined to the shaft 55 is a collar 57, which carries a pair of oppositely disposed bevel gears 58 and 59. These gears are arranged to mesh with a bevel gear 60 fixed to a shaft 61 having its axis parallel 125 130

with that of armature 12, and journaled in the bracket 37 and also in bracket 39. Upon this shaft 61 are fastened the pinions 62 and 63 which are in mesh with gears 44 and 45. 5 By sliding the collar 57 either to the right or left, either one or the other of bevel gears 58 and 59 may be made to mesh with the gear 60, and in this way cause rotation of the frame 40 and brushes 15 and 16 in either direction. 10 To effect this movement of the collar, a lever 67 pivoted at 64 has a forked portion 65 engaging a groove 66 in the collar 57. The other end of this lever 67 is adapted to be pulled in one or the other direction by either 15 of two electromagnets 68 and 69, in opposition to the force exerted by the two opposed springs 70 and 71 acting on the lever 67 to return it to a neutral position, with neither of the bevel gears 58 or 59 in mesh with the gear 20 60. With neither electromagnet 68 or 69 energized, these springs 70 and 71 maintain the lever 67 in its central position, and in this way rotation of shaft 55 is ineffective to rotate the brushes 15 and 16. In order to set 25 the course by rotating these brushes, one or the other of the electromagnets 68 and 69 is energized, as by a push button control, and during the energization one of the gears on collar 57 is in mesh with the gear 60 to effect 30 the proper rotation of shaft 61 and brushes 15 and 16. In order to damp out any possible oscillations which might otherwise occur following an operation of either of the electromagnets 68 and 69, dash pots 72 and 73 are 35 provided operatively connected with the end of lever 67.

An appropriate indicating device may be provided for showing the extent of rotation of the brushes effected by the arrangement 40 just described. This indication may be transmitted to any desired point or points by the aid of well-known devices, such as by 45 electromagnetic apparatus, although for the sake of simplicity the indicator 74 is shown 50 in this instance as mounted directly on the outside of frame 29. This indicator coacts with a dial 75, and is driven from the shaft 61 by the aid of a system of gears such as the bevel gears 76 and 77. Preferably I so 55 choose the gear ratios in this system that the indicator 74 moves over the same angle as the brushes for a definite amount of rotation of shaft 61, since under such circumstances the actual meridian steered by may be indicated by the pointer 74.

In order to prevent creeping of the brushes 15, 16 over the commutator 14, in the direction of rotation of armature 12, there may be 60 provided a brake 78 normally applied to the fraction wheel 79 by means of a spring 80. This wheel 79 is in mechanical connection with the frame 29 through a shaft 81 rotatably mounted in the frame and carrying the pinions 82 and 83 which are in mesh with 65 the gears 44 and 45. The shaft 81 may be

appropriately supported by the aid of brackets 37 and 39. When it is desired to set the brushes 15, 16 into a new position with respect to the body to be steered, the brake 78 may be released by the action of an electro- 70 magnet 84, arranged to be energized whenever either of the two electromagnets 68 and 69 is energized.

If it be desired to maintain the axis of armature 12 more exactly in a vertical direction, use may be made of gyroscopes appropriately connected to the axis of suspended frame 29 so as to augment the effect of the small amount of pendulosity of the frame. A substantial amount of gyroscopic action is 80 however produced by the rapid rotation of the armature 12. In this way the immunity of the system from short period ballistic disturbances may be materially increased. Furthermore since the operation of the entire instrument is based upon the induction of electromotive forces by the rotation of the armature 12 in a component of terrestrial magnetism, it is important to prevent the distortion 85 of this magnetism to the greatest possible extent. For this purpose there should be no soft iron or other magnetic material in the vicinity of the armature; and stray fields from electromagnetic apparatus such as motor 17 and electromagnets 68, 69 and 84 should be minimized by locating them at a distance, and if necessary by screening them by means of a 90 light iron screen 85. This screen serves to intercept the stray fields of the leakage fluxes. In addition it is preferable to use alternating 95 current magnets instead of direct current. Wires carrying currents in the vicinity of the armature 12 should be so paired off or associated with each other as to form substantially perfect bifilar systems with negligible external magnetic effects. When all these 100 precautions are taken, the field of terrestrial magnetism is maintained uniform, and the disappearance of potential difference across the brushes 15 and 16 while the armature 12 is rotated, indicates that the brush axis, and therefore the horizontal axis of reference of the stabilized body, is in a definite angular 110 position with respect to the direction of the horizontal component of the terrestrial magnetism. 115

The instrument of Figs. 2 and 3 if operated at a speed high enough and if constructed to have a large enough number of turns in series with the brushes 15 and 16, is capable of generating an E. M. F. which is more than sufficient to provide the necessary controlling effects. 120

Returning now to the circuit diagram of Fig. 1, the brushes 15 and 16 are shown as 125 connected to the terminals of a very high resistance 86. The value of this resistance is made many times greater than the resistance of the armature 12, so that the difference of potential of the terminals 87 and 88 is very 130

nearly equal at all times to the E. M. F. induced in the armature.

In order to amplify the controlling effects, the thermionic tubes 26, 27 and 28 are utilized. The central point 89 of the resistance 86 is connected to the filament 90 of the first tube 26. This tube is shown as being provided with two controlling grids 91 and 92, and two plates 93 and 94, the grid 91 being disposed between filament 90 and plate 93, and grid 92 between filament 90 and plate 94. It is thus seen that this tube 26 is a double tube of the so called pliotron type, and has two input and two output circuits. The terminal 87 of resistance 86 is connected to grid 91, so as to affect the output current between filament 90 and plate 93. The terminal 88 is similarly connected to the grid 92, so as to affect the output current between filament 90 and plate 94. The heating of the filament 90 may be effected by the aid of the battery 95. A source of direct current E. M. F. such as the battery 96 is used for the plate or output circuits, which may be traced as follows: from the lower positive terminal 107 of battery 96, through wires 97, 98, to point 99, where the current divides—one branch flowing through adjustable resistance 100, contact finger 101, the primary 102 of a transformer 103, plate 93, filament 90, point 104, wires 105 and 106, to the upper negative terminal 108 of battery 96. The other branch from point 99 flows through adjustable resistance 109, contact finger 110, the primary 111 of a transformer 112, plate 94, to filament 90, from which the two currents flow in the same path to the negative terminal 108, through wires 105 and 106.

As is now well known, the properties of such a vacuum tube as 26 are such that the plate currents flowing through the circuits just traced may be varied by varying the potentials of the controlling grids 91 and 92 relative to the filament 90. Thus if this potential is positive, the plate current is increased, and if it is negative, the plate current is reduced. The connection of the grids 91 and 92 to the terminals 87 and 88 of resistance 86 provides a means for varying these plate currents in response to the variations in the position of brushes 15, 16 relative to the direction 13 of the horizontal component of the terrestrial magnetism. Thus while the brushes are in the zero E. M. F. position, the potential difference between filament 90 and either of grids 91 and 92 is zero. Assuming that transformers 103 and 112 are similar, resistances 100 and 109 equal, the plate currents in the two branches are equal. If however the brushes are displaced a slight amount in a clockwise direction, which as we have already assumed, makes brush 15 positive with respect to brush 16, then grid 92 is positive with respect to the filament 90, while grid 91 is negative with respect thereto. This causes the plate current between filament 90 and plate 94 to be greater than that between this filament and plate 93. The potential drop across resistance 109 is therefore greater than that across resistance 100. Since one terminal of each of these resistances is connected to the positive terminal 107 of battery 96, this variation in drop causes the negative terminal 113 of resistance 109 to be at a lower potential than the negative terminal 114 of resistance 100. This difference in potential between points 113 and 114 is much greater, due to the amplifying effect of the tube 26, than the potential difference across brushes 15, 16.

Had the brush axis been displaced in a counter-clockwise direction, the effects just noted would have been reversed, with the ultimate effect that point 113 would have been at a higher voltage than the point 114. The potential difference between these two points is dependent solely upon the deviation of the brush axis from the zero E. M. F. position, and represents one of the elements upon which the control is based.

The transformers 103 and 112 having primary coils 102 and 111, and secondary coils 115 and 116, are provided for contributing another element to the control which is proportional to the velocity of the deviation, or in other words to the first derivative with respect to time of this deviation. While the currents through the primaries 102 and 111 are steady and unvarying, there can be no E. M. F.'s induced in the secondary coils 115 and 116. This condition is that when the brushes 15 and 16 occupy a steady position, or in other words, while there may be a deviation of the body there is neither an increasing nor a decreasing deviation. Thus the transformers are ineffective to create an E. M. F. when the deviation is steady. However, as soon as the brushes move, the currents through the primaries 102 and 111 vary, and the rate of variation is substantially proportional to that of the angular velocity of the brushes 15, 16, due to the fact that the variation in plate current through tube 26 may be made to be proportional to the variation in the grid potential. Such a variation in current induces an E. M. F. in the secondaries 115 and 116. If both transformers 102 and 111 are wound in the same direction and coils 115 and 116 have their lower terminals connected, as shown, then it can be demonstrated by Lenz's law of induction that an increase in current in primary coil 111 due to a clockwise movement of the brushes, and a corresponding decrease in current in coil 102 causes E. M. F.'s to be induced in the coils 115 and 116 in the direction shown by the arrows placed near the coils. Thus the upper terminal of coil 116 is positive, while that of coil 115 is negative, as regards the common lower terminal. Movement of the brushes in

a counterclockwise direction affects the potentials of the coils 115 and 116 in the opposite sense, making the upper terminal of coil 115 positive as regards the terminal of coil 116.

5 In order to affect the generator 21 in response to these varying relative potentials, the generator is provided with pairs of opposed exciting coils 117, 118, and 119, 120. The coils 117 and 118 are connected in the 10 plate circuits of the second tube 27. The filament 121 of this tube is heated by battery 95, and is connected, by the aid of wire 103 to the negative terminal 108 of battery 96. The control grids 123 and 124 are connected 15 respectively to terminals 114 and 113 of the resistances 100 and 109. Under the conditions we have assumed heretofore, the grid 123 will be positive with respect to grid 124, with the result that more current will be permitted to 20 flow in the plate circuit controlled by grid 123 than in that controlled by grid 124. The plate circuit controlled by grid 123 includes battery 96, a switch 122, coil 117, plate 125 and filament 121. The plate circuit controlled by grid 124 includes battery 96, switch 122, coil 118, plate 126 and filament 121. The coil 117 normally exactly annuls 25 the effect of coil 118, when the grids 123 and 124 are at the same potential, which condition 30 corresponds to zero deviation of the brushes. A deviation in a clockwise direction as has been assumed, thus increases the current through coil 117 and decreases it through coil 118. The result is that the latter coil is overpowered, and an appreciable excitation is supplied to the generator 21. This in turn causes 35 the generation in this machine of an E. M. F. which is substantially proportional to the deviation of the brushes 15, 16. Since the motor 40 20 is connected directly to the generator 21, the rudder 170 or other stabilizing element is moved with a speed proportional to the brush deviation by means of the motor shaft 25. The connection between the shaft and 45 the rudder 170 must of course be such that the rudder will be moved to bring the body to be stabilized back to its desired position. In order to insure substantial proportionality 50 between the deviation of the brushes and the speed of motor 20, the tubes 26 and 27 are operated on that portion of the tubes' characteristics which is linear, as is well understood. This linear characteristic is of great importance, and it has been assumed herein 55 that double tubes of the sort illustrated can be constructed to provide this linear characteristic, and that no material interference exists between the two electron paths in the tubes. This condition can of course be still 60 more closely approximated with tubes having only single grids and anodes, as in some of the later modifications which I shall describe. For this reason also it is advisable to work machines 20 and 21 below their saturation point. If the brushes were displaced

in a counter clockwise direction, then by tracing out the corresponding variations in current flow, it is possible to show that coil 118 receives more current than coil 117, with the result that the E. M. F. generated in generator 70 21 is opposite in sense to what it was in the first case, and the motor 20 is rotated in a reverse direction, but in the proper direction to bring the body back to zero deviation. The excitation for the motor 20 is effected by 75 means of coil 127 connected in series with an adjustable resistance 128 and fed from any appropriate D. C. source such as the battery 96.

While the coils 117 and 118 are made to 80 excite the generator 21 to an extent which is proportional to the brush deviation, the coils 119 and 120 produce an excitation which is proportional to the velocity of deviation. For this purpose these coils are located in the 85 plate circuits of the thermionic tube 28. The battery 96 is again used for the source of potential in this circuit, and its negative terminal 108 is connected to filament 129 of this tube. The filament is also connected to the 90 common lower terminal of secondary coils 115 and 116. The control grids 130 and 131 are respectively connected to the upper terminals of the coils 115 and 116; as is evident the potential of these grids are equal when 95 the deviation is steady. Under such circumstances the plate currents are both equal; one through battery 96, switch 122, coil 119 and plate 132, the other through battery 96, switch 122, coil 120 and plate 133, to filament 100 129 and thereby back to the negative terminal of battery 96. If however, the deviation increases in a clockwise direction, grid 131 becomes positive with respect to grid 130, and more current flows through coil 120 than 105 through coil 119. The result is a proportional additional excitation for generator 21, in the proper direction to influence the motor 20 to wipe out this velocity of deviation. For 110 velocity in a counterclockwise direction, opposite effects are obtained, and coil 119 would overpower coil 120.

From the foregoing considerations, the operation of the device to produce "dead beat" steering may now be explained. As the deviation increases from zero say in a clockwise direction, coils 117 and 120 will predominate, and they will assist each other to wipe out both deviation and velocity of deviation. The coil 120 thus produces a properly timed "meeting" action, which gradually reduces to zero as the speed of deviation vanishes. Under such circumstances the coil 117 alone controls the apparatus. When the body starts to swing back, the coil 117 115 still predominates over coil 118, but now coil 119 overcomes 120 and produces properly timed "easing" action, opposed to that of the positional control coil 18. Heretofore such "meeting" and "easing" actions were left to 120 125 130

the judgment of the helmsman, with the result that the actions were not very accurately produced. On the other hand, the arrangement just described automatically produces 5 these actions at the proper time, and there is an attendant very rapid wiping out of any deviations due to accidental disturbances.

If the body swings in a reverse or counter-clockwise direction, the "meeting" and "easing" actions will of course be also reversed, 10 so that again the proper forces are brought into play to return the body to its undeviated position and keep it there.

In the diagram of Fig. 1 I show the electromagnets 68, 69, and 84, connected to the battery 96 or other source, which magnets as explained hereinbefore are utilized for setting the course of the body. Push buttons 134 and 135 may be utilized to energize the 20 magnets. Thus while button 134 is operated, magnets 69 and 84 are energized, and the brushes 15, 16 are moved in one direction by the aid of the transmission and gearing shown in Fig. 2. If however push button 25 135 be operated, then magnets 68 and 84 are energized and the brushes are moved in the other direction. This system of brush shifting affords a very simple and convenient means for steering the vessel or airplane 30 manually, if it be necessary to reset the course at any time. While the brushes are being set by this means, the body is turned to the new course by the aid of the controlling devices just described, wherein the inequality 35 of the currents in branches 100, 102 and 109, 111, causes a prompt response by the rudder to turn the vessel to the new position corresponding to the setting of the brushes.

I also show in Fig. 1 the coils 41, 42 which 40 have an axis always perpendicular to the line of the brushes. These coils may be used optionally to increase still further the effect of any slight brush deviation. By opening the switch 122, it is possible to render these 45 coils active, since then the short circuit across the terminals of the coils is removed. When this is accomplished, current may enter through collector rings 50 and 51, into coils 41, 42 respectively and return through wire 50 136 and ring 49 to any appropriate source, such as battery 96. Since the coils 41, 42 are wound in opposite directions and have equal numbers of turns, they are ineffective 55 to influence the E. M. F. across brushes 15, 16 when the current flow is the same in each. This is the condition when there is neither any yaw nor any velocity of yaw, as is apparent by tracing the complete circuit for 60 these coils. The circuit for coil 41 may be c0 traced from positive terminal of battery 96, collector ring 49, wire 136, coil 41, collector ring 50, exciting coils 117 and 120 in parallel, plate circuits 125, 121 and 133, 129 in parallel to the negative terminal of battery 96. The

circuit for coil 42 is similar, except that it 65 flows through coils 118 and 119 in parallel, as well as plate circuits 126, 121, and 132, 129. While there is no yaw, the current through plate circuit 125, 121 and coil 117 is equal to that through circuit 126, 121 and 70 coil 118; and while there is no velocity of yaw the same may be said of the plate circuits in which coils 119 and 120 are located. Under such circumstances, therefore, the combined current through coils 117 and 120 75 is equal to that through coils 118 and 119, so that both of the exciting coils 41, 42 for the instrument 11 receive the same current, and their magneto-motive forces are entirely neutralized. If however, there is a slight amount 80 of yaw say in a clockwise direction, more current flows through coil 117 than through coil 118, with the result that the current through exciting coil 41 is greater in proportion than through coil 42. For a clockwise velocity of 85 yaw, this effect is still more pronounced, since more current flows through coil 120 than through 119. Thus during this stage of the angular motion, the magnetomotive force of coil 41 will overpower that of coil 42, and the 90 resultant vector of transverse magnetization H_c will be directed to the west. This vector in combination with the horizontal component of terrestrial magnetism H produces a 95 resultant horizontal magnetizing force H_r , greater in magnitude and forming a larger angle α_r with the line of brushes than merely the component H of the terrestrial magnetism. This results in the building up of an 100 increased voltage across brushes 15, 16, and consequently still greater action H_c of the coils 41, 42 and so on. Upon reversal of the 105 angular velocity of the ship, the action of the velocity control effected by the relay 28 serves to reduce the angle α_r , with a consequent reduction in the component H_c . It is thus seen that the action of the cross magnetizing coils 41 and 42 serves to emphasize or magnify the actions of the relays 27 and 28 which act in response to the positional 110 function and to higher time derivatives thereof. It is important, when cross magnetizing coils such as 41, 42 are used, to be certain that conditions are not created under which the whole system becomes self excited. If 115 that should happen the circuits would have such flow of currents as would bring the vacuum tubes to the point of saturation, without the continuity of regulation as a function of the disturbing angular motion. 120 It is important therefore in this case when such coils 41, 42 are used, not to increase either the amplification of the vacuum tubes or the coefficient of mutual inductance between the coils 41, 42 and the armature 12 125 beyond a certain critical value, at which the system becomes self-excited. In case the coils 41, 42 are not used, it is of course possi-

ble to provide for any desired amplification, since under such circumstances self-excitation can never occur.

With the device as thus described, it is impossible for the vessel or other object to deviate to any substantial degree from her course. Even in the case of aerial navigation, where disturbing accelerations may act very persistently and disturb the direction of freely suspended objects from the vertical, my device as described prevents all possibility of extensive yawing, and the result is that the centrifugal horizontal accelerations are also reduced, if not entirely eliminated. It is thus possible to preserve the vertical position of armature 12 very accurately. Even if this were not possible, and if the armature should happen to precess in space so as to trace the cone O, 1, 2, 3, 4, about the true vertical OV of Fig. 7, the directional properties of the automatic steering derived from the position of the armature are not materially affected. The only difference will be that only the values of the controlling forces will be altered slightly, but not their directions. Thus in Fig. 7 if OH represents the direction of the terrestrial magnetism, the armature 12 will be the more strongly excited the nearer its axis is to a position perpendicular to this direction. Thus if the armature axis is in the position O1, the exciting component of OH is OH₁, which is larger than if the armature were in the truly vertical position OV. In this vertical position the exciting component of OH is represented by OH₅. If however the armature axis swings to O3, the exciting component reduces to OH₃, which is less than in either of the other cases, since the direction O3 is more nearly parallel with OH than these prior discussed positions. The only effect of this precession or deviation therefore is to weaken or strengthen the excitation of the armature 12, but the position about which the body is finally stabilized is not at all altered.

In the embodiment of my invention illustrated in Fig. 1, I show two separate tubes 27 and 28, one producing a positional controlling action, and the other a velocity controlling action, which actions are transmitted to the exciting coils 117, 118, 119, and 120. Instead of combining the controlling actions in the field of generator 23, it is possible to combine them in other ways. In Fig. 4 by way of a further example I have shown this combination effected in the circuits for controlling a vacuum tube 137, which tube replaces the two tubes 27 and 28 of Fig. 1. The grids 91 and 92 of the tube 26 in Fig. 4 are connected to resistance 86 in precisely the same manner as before, but in the plate circuits are inserted the variable inductances 138 and 139. The points 140 and 141 are connected to the grids 142 and 143 of tube 137. As long as the currents through the plate circuits

100—138, and 109—139, of tube 26 are steady and unvarying, which corresponds to either zero deviation or to a constant deviation of the stabilized body from its position, the potential differences between points 99 and 140 on one hand, and points 99 and 141 on the other hand are due solely to the ohmic drop across the resistances 100 and 109. If these currents are varying, however, additional electromotive forces appear, which are due to the self induction of coils 138 and 139. These E. M. F.'s are equal to

$$-L_1 \frac{di_1}{dt}$$

and

$$-L_2 \frac{di_2}{dt},$$

where L₁ and L₂ denote the coefficients of self induction of coils 138 and 139, and i₁ and i₂ the instantaneous values of the currents in the branches 100, 138 and 109, 139. The action of coils 138, 139 on the circuits of vacuum tube 137, and therefore on the controlling equipment, is exactly the same as the action of transformers 103, 112 and tube 28 of Fig. 1. Only two exciting coils 144, 145 are needed, which are differentially arranged and are located in the plate circuits of tube 137. The wires 146 may lead to collector rings 49, 50 and 51 as in Fig. 1 for the purpose of utilizing the coils 41, 42 on the armature 12, and thus of obtaining a sharper and quicker response of the apparatus.

By varying the amount of resistance or inductance in series with the grid controlling circuits in the embodiments shown in Figs. 1 and 4, as by means of the sliding contacts 101, 110, and 147, 148, it is possible to regulate the performance of the automatic steering device to meet widely varying conditions of navigation. Thus for example when the sea is quiet and it is desired to steer a very accurate course, more resistance and inductance will be introduced in the circuit, and the device will respond even to very slight deviations of the ship from her course, as well as to very small angular velocity of yawing. Should however the sea be rough, when it is unnecessary and undesirable to have the vessel react against each individual impulse or wave, and it is merely desired to maintain an average course, less inductance and resistance will be used. Furthermore by varying the relative values of the inductances 138, 139, in circuit with respect to the corresponding resistances 100 and 109, the damping coefficient which determines the persistence of the oscillations can be varied. By varying the resistances 100 and 109 in opposite directions by means of contacts 101 and 110, the steered course can be varied slightly or adjusted without making use of the brush shifting arrangement. Finally when under the influence of wind, trim and other factors,

the ship or other steered body has any tendency to yaw to one side more violently than to the other, this tendency to unsymmetrical yawing can be counteracted by offsetting the controlling inductances in opposite directions by means of the sliding contacts 147 and 148, until the required counteracting effect is obtained.

In Figs. 1 and 4, controlling effects are obtained which are responsive only to the extent of deviation and to the first derivative with respect to time of this deviation. It is a simple matter to extend the principles enunciated herein to provide controlling effects based upon higher time derivatives of the deviation. Thus in Fig. 1 if primary coils of transformers be inserted in the plate circuits of tube 28, between plates 132 and 133 and coils 119 and 120, and if the secondary E. M. F.'s be impressed on the grids of an additional tube in the same manner as explained in connection with grids 130 and 131 of tube 28, I may obtain from such an additional tube a controlling action in phase with 25 and proportional to the angular acceleration of the yaw. In an entirely analogous manner still higher time derivatives may be obtained for the controlling actions, and thus as rapid and as sharp anticipatory actions 30 as desired in the control either for stabilizing or steering may be produced. By giving predominance to the accelerational control, the controlling action will be started always in phase with the disturbing torque, 35 since this torque in virtue of the fundamental law of dynamics is in phase with the angular acceleration. In this way the disturbing forces are made of no effect by neutralizing the disturbing torque, as distinguished from 40 the older systems based only on positional control, wherein no counteraction is produced until the effect of the disturbing torque (that is, the deviation) has developed.

The controlling actions excited by my system will be practically devoid of any time lag since it is a well known fact that thermionic vacuum tubes have no inertia lag and react substantially instantaneously to the grid control. Due to this continuity of the 50 control the rudder is moved by the motor 20 continuously in step with the control taking place on the field of the generator 23, and the whole performance is rendered rapid and continuous.

Instead of using the so-called Ward Leonard system of control shown in Fig. 1, which is based upon the use of a variably excited generator 23 feeding a constantly excited motor 20, it is obviously possible to use other 60 control systems such as relays, solenoids, electromagnets and the like to accomplish substantially identical controlling functions.

In the embodiments thus far described, the controlling effects are immediately utilized 65 to bring back the body to a certain predeter-

mined position. However, my invention is much broader than this, since the controlling action may be utilized to influence only a small follow up motor which may serve to rotate the brushes 15, 16 to a position where 70 there is no longer any difference of potential across them. Such a system is illustrated in Fig. 5, where the small motor 149 is actuated to rotate the gear 150 driving the brushes around the shaft 18 of armature 12. 75 Of course in this case the controlling system need not be so refined as in the case where the steered body is controlled. The follow up motor 149 may readily be controlled from the system shown in Fig. 4. There are two 80 oppositely wound field coils 151 and 152 in series with the armature of motor 149. These coils are in the plate circuits of a tube entirely similar to tube 137 of Fig. 4, the lead 153 going to the left hand plate, lead 154 to 85 the right hand plate, and lead 155 to the positive terminal of battery 96. The effect of the control in response to velocity of deviation is to eliminate hunting of the follow up motor 149, which is generally highly undesirable. This motor as shown in Fig. 5 is 90 capable of performing other functions in addition to or in place of its "follow up" duty, such as for controlling functions used in connection with gyroscopic compasses, as for example to actuate remote control indicating repeaters, to impress controlling movements upon automatic steering devices of vessels, and the like. It would of course be also possible to provide here also, coils such as 41, 42 95 of Fig. 1 if greater sharpness of the follow up performance is desired. When so used these coils can be operated either below or above the point of self-excitation; in general, it is more desirable to provide such coils in 100 the case of a follow up system such as shown in Fig. 5, and even to adjust them above the point of self-excitation than in the system of Fig. 1, where extreme sharpness of control 105 may have some effect in destroying the smooth continuous action desired. 110

Although in all of the modifications thus far described, pliotron tubes with double plates are shown, it is of course possible to substitute the commoner three-electrode tubes, as shown in Fig. 6. In this figure two tubes 156 and 157 replace the tube 26 of Figs. 1 or 4. In this instance the plates 93 and 94 are located one in each tube, and there are also two filaments 90 and 90'. The grids 91 and 92 connect, by the aid of leads 158 and 159, with opposite terminals of a resistance such as 86 of Fig. 1. The leads 160 and 161 from the plates 93 and 94 connect to appropriate resistances and inductances as illustrated in the prior figures. In all respects the control when using such single tubes may be made identical with those already described. In other respects also, various modifications may be resorted to in the 125 130

schemes shown. Thus still other types of vacuum tubes may be utilized, or in fact other sensitive relays such as of the polarized type may be substituted to perform the follow up 5 functions although without the continuity of action afforded by vacuum tubes.

I claim:

1. In a system for stabilizing a body about a definite direction, a dynamo electric machine adapted to be excited by the field of 10 terrestrial magnetism to a substantial degree, and means for controlling the body by the aid of the electromotive force generated by said machine, comprising means affecting 15 the body in such manner that its controlling action on the body varies with each variation of the said electromotive force.

2. In a system for stabilizing a body about a definite direction, a dynamo electric armature rotating in the field of terrestrial magnetism, a pair of brushes for the armature, 20 stationary relatively to the body, and means for continuously controlling the position of the body so as to maintain the E. M. F. across 25 the brushes at a minimum, comprising means affecting the body in such manner that its controlling action on the body varies with each variation of the said electromotive force.

3. In a system for stabilizing a body about a definite direction, a dynamo electric machine adapted to be excited to a substantial 30 degree by the field of terrestrial magnetism, the position of the axis of the machine having a definite direction with respect to the body, and means for continuously controlling 35 the position of the body in accordance with the E. M. F. generated in the machine and varying with each variation of the position of the body with respect to the terrestrial field.

4. In a system for stabilizing a body about a definite direction, means for generating an 40 E. M. F. substantially proportional to the deviation of the body from a predetermined 45 magnetic meridian, and means for continuously controlling the body in accordance with a function of this E. M. F., comprising means affecting the body in such manner that 50 its controlling action on the body varies with each variation of the said electromotive force.

5. In a system for stabilizing a body, means for creating an electromotive force 55 that is substantially continuously variable in accordance with the extent of deviation of the body from the desired position, and means for controlling the body to return it to its desired position, in accordance with a 60 function of the electromotive force, comprising means affecting the body in such manner that its controlling action on the body varies with each variation of the said electromotive force.

65 6. In a system for stabilizing a body about

a definite direction, a dynamo electric armature adapted to generate an E. M. F. by rotation in the terrestrial magnetism, a pair of brushes for tapping the armature having a definite axis with respect to the body to be 70 stabilized, and means for continuously controlling the position of the body in accordance with a function of the E. M. F. across 75 the pair of brushes, comprising means affecting the body in such manner that its controlling action on the body varies with each variation of the said electromotive force.

7. In a system for stabilizing a body about a definite direction, a dynamo electric armature adapted to generate an E. M. F. by rotation in the terrestrial magnetism, means for 80 maintaining the axis of the armature vertical, a pair of brushes stationary relative to the body for tapping the armature, and means for continuously controlling the position of the body in accordance with a function of the E. M. F. across the brushes, comprising means affecting the body in such manner that its controlling action on the body varies with each variation of the said 90 electromotive force.

8. In a system for stabilizing a body about a definite direction, a dynamo electric armature adapted to generate an E. M. F. by rotation in the terrestrial magnetism, a pair of 95 brushes tapping the armature at points stationary relative to the body, and means for controlling the body in accordance with the value of the E. M. F. across the brushes and also with the value of the rate of change of 100 the E. M. F.

9. In a system for stabilizing a body about a definite direction, a dynamo electric armature adapted to generate an E. M. F. by rotation in the terrestrial magnetism, means for 105 tapping the armature at points stationary with respect to the body, a member for controlling the position of the body, and means for moving this member with a speed corresponding to a function of the E. M. F. across the tapped points, said speed varying with each variation of the said electromotive force.

10. In a system for stabilizing a body about a definite direction, a dynamo electric 110 armature adapted to generate an E. M. F. by rotation in the terrestrial magnetism, means for tapping the armature at points stationary 115 with respect to the body, a member for controlling the position of the body, and means for moving this member with a speed corresponding to the E. M. F. across the tapped points and the rate of change of 120 this E. M. F.

11. In a system for stabilizing a body about a definite direction, means for producing an E. M. F. which varies substantially in proportion to the extent of deviation of the body, means for deriving an E. M. F. from this first E. M. F. which varies substantially 130

- in proportion to the rate of change of the first E. M. F., and means for controlling the position of the body in accordance with a function of the values of these E. M. F.'s. 65
- 5 12. In a system for stabilizing a body about a definite direction, means for producing an E. M. F. which varies substantially in proportion to the extent of deviation of the body, means for deriving an E. M. F. from this 10 first E. M. F. which varies substantially in proportion to the rate of change of the first produced E. M. F., a rudder-like member for controlling the position of the body, and means for moving this member with a speed 15 corresponding to a function of the values of the E. M. F.'s. 70
13. In a control system, means for generating an E. M. F., means for deriving an E. M. F. which varies substantially in proportion to the rate of change of the generated E. M. F. and a controlling means affected by both of these E. M. F.'s. 75
14. In a system for stabilizing a body about a definite direction, means for generating an E. M. F. which varies substantially in proportion to the deviation of the body from its required position, means for deriving an E. M. F. which varies substantially in proportion to the rate of change of the generated E. M. F., and means, affected by both these E. M. F.'s, for controlling the position of the body. 80
15. In a system for stabilizing a body about a definite direction, a dynamo electric armature rotated in the terrestrial magnetic field, a pair of brushes for tapping the armature at points that are relatively stationary with respect to the body, means for further exciting the machine along an axis having a constant relation with the axis of the brushes, said means becoming energized upon movement of the body from its desired position, and rudder-like means for controlling the position of the body, affected in accordance 45 with the E. M. F. across the brushes. 85
16. In a system for stabilizing a body about a definite direction, a dynamo electric armature rotated about an axis having a definite relation to the body to be stabilized, means 50 for exciting the armature in a direction corresponding to the direction of the terrestrial magnetic field, a pair of brushes tapping the armature on an axis that is stationary with respect to the body to be stabilized, means for 55 energizing the armature about an axis fixed with respect to that of the brushes, and a rudder-like member for controlling the position of the body, affected in accordance with the E. M. F. across the brushes. 90
- 60 17. In a system for stabilizing a body about a definite direction, a dynamo electric armature rotated in the terrestrial magnetic field so as to be influenced thereby, means for maintaining the axis of the armature substan- 95
- tially vertical, a rudder-like member for controlling the position of the body, and means for moving this member at a speed corresponding to a function of the E. M. F. generated across two points of the armature which are stationary with respect to the body to be stabilized. 100
18. In a system for stabilizing a body about a definite direction, a dynamo electric armature rotated in the terrestrial magnetic field so as to be influenced thereby, means for maintaining the axis of the armature substantially vertical, a rudder-like member for controlling the position of the body, a motor for moving said member, and means for impressing upon the motor an E. M. F. which is a function of the E. M. F. generated in the dynamo electric machine across two points which are stationary with respect to the body to be stabilized, said impressed E. F. M. varying with each variation of the generated E. M. F. 105
19. In a system for stabilizing a body about a definite direction, means for producing an E. M. F. varying substantially in proportion to the extent of deviation of the body, means for amplifying said E. M. F., a rudder-like member for controlling the position of the body, and means for moving this member with a speed corresponding to a function of the amplified E. M. F., said speed varying 90 with each variation of the said electromotive force. 95
20. In a system for stabilizing a body about a definite direction, a dynamo electric armature rotating about a vertical axis, means for exciting the armature in accordance with the horizontal component of the terrestrial magnetism, means for tapping said armature at a pair of points that are stationary relatively to the body to be stabilized, a rudder-like member for controlling the position of the body, and means for moving said member with a speed corresponding to the variations in the E. M. F. across the points and also to a time derivative of this E. M. F. 110
21. In a system for stabilizing a body about a definite direction, means for generating an E. M. F. varying substantially in proportion to the deviation of the body from its required position, an electronic emission device for amplifying the variations in this E. M. F. both as to direction and amount, and means for controlling the position of the body, operated in response to a function of the E. M. F. 115
22. In a system for stabilizing a body about a definite direction, means for generating an E. M. F. varying substantially in proportion to the deviation of the body from its required position, an electronic emission device for amplifying the variations in this E. M. F. both as to direction and amount, a rudder-like member for controlling the position of the body, and means for moving the rud- 120
- 125

der-like member at a speed substantially proportional to a function of the E. M. F. generated.

23. In a system for stabilizing a body about a definite direction, a dynamo electric machine excited by the horizontal component of the terrestrial magnetic field, means for tapping the armature at a pair of points stationary relative to the body to be steered, an electronic emission device for amplifying the variations in the E. M. F. across the points, both as to direction and amount, and means for controlling the position of the body operated in accordance with the amplified variations 15 and also with a time derivative of the variations.

24. In a system for stabilizing a body about a definite direction, means for generating an E. M. F. varying substantially in proportion 20 to the deviations of the body from its required position, both in direction and amount, an electronic emission device for amplifying this E. M. F., a generator, means for exciting this generator in accordance with the amplified E. M. F. and also in accordance with a time derivative of the E. M. F., a motor fed from the generator, and a rudder-like member moved by the motor.

25. In a system for stabilizing a body about a definite direction, a rotating dynamo electric armature for generating an E. M. F. occasioned by the field of terrestrial magnetism, a pair of brushes tapping the armature at points stationary relative to the body to be stabilized, a resistance having a high value compared with that of the armature, said brushes being connected across the resistance, an electronic emission device having a pair of control electrodes also connected across the resistance, and an electron emitting electrode connected to a central point of the resistance, a pair of output circuits for the device, each including a resistance, a generator, means for exciting the generator in accordance with the difference in the potential drop across the two resistances in the output circuits, a motor fed from the generator, and a rudder-like member moved by the motor.

26. In a system for stabilizing a body about a definite direction, the elements as set forth in claim 25, with the addition of an inductance in each of the output circuits, and additional means for exciting the generator in accordance with this difference in potential drop across the two inductances.

27. In a system for stabilizing a body about a definite direction, the elements as set forth in claim 25, with the addition of an inductance in each of the output circuits, additional means for exciting the generator in accordance with the difference in potential drop across the two inductances, and a pair of electronic emission devices for amplifying the effects of these differences in potential drops.

28. In a directional responsive electric system, a dynamo electric armature excited by the field of terrestrial magnetism, a pair of brushes stationary relatively to the body, means for controlling the position of the body 70 operated in accordance with variations in E. M. F. across the brushes due to variations in position of the body, and means for accentuating the variations in E. M. F. comprising a coil for exciting the armature along an axis 75 having a position constant with respect to that of the brushes, and means for energizing this coil in accordance with a function of the E. M. F. across the brushes.

29. In a directional responsive electric system, the elements as set forth in claim 28, with the limitation that the accentuating coils are energized in accordance with the E. M. F. across the brushes and also with a time derivative of this E. M. F. 80

30. In a directional responsive electric system, the elements as set forth in claim 28, with additional means for energizing the generator substantially in accordance with a time derivative of the deviation. 85

31. In a system for stabilizing a body, means for creating an electromotive force that is substantially continuously variable in accordance with the extent of deviation of the body from its desired position, means for creating another substantially continuously variable electromotive force that is a derivative with respect to time of the first mentioned electromotive force, and means for controlling the body to return it to its desired 95 position, in accordance with the combination 100 of the two electromotive forces.

32. In a system for stabilizing a body, means for creating an electromotive force that is substantially continuously variable in 105 accordance with the extent of deviation of the body from its desired direction, and means for producing a torque continuously dependent upon the value of this electromotive force for returning the body to its desired direction, 110 said torque varying with each variation of said electromotive force.

33. In a directional responsive electric system, means for creating a substantially continuously variable electromotive force, that is 115 a function of the directional condition of the device to be controlled, means for deriving from said electromotive force, another electromotive force varying as the rate of change of the first electromotive force, and means for 120 creating a controlling effect in accordance with both of these electromotive forces.

34. In a directional responsive electric system, means for creating a substantially continuously variable electromotive force, that is a function of the directional condition of the device to be controlled, means for deriving from said electromotive force, another electromotive force that is a time derivative 125 of the first electromotive force, and means for 130

15

creating a controlling torque that is a function of both of these electromotive forces.

35. In a directional responsive electrical system, a dynamo electric armature having an excitation that is substantially constant in direction, and a pair of tap points for the armature, for generating an electromotive force which varies with the relative position of the tapped points and the excitation, controlling means operated continuously in response to a deviation of the taps from a definite relative position with respect to the excitation, and means for accentuating the

potential difference variation between the tap points in response to such deviation.

36. In a directional responsive electrical system, the elements as set forth in claim 35, with the limitation that the accentuating means comprise exciting coils having an axis fixed as regards the tap points and energized in response to the deviation of the position of the tap points.

In testimony whereof, I have hereunto set my hand.

NICOLAI MINORSKY.
